FIG. 1

FIG. 2

FIG. 3

FIG. 4

FIG. 5

FIG. 6

FIG. 1 is a side elevational view showing my new design for a multipurpose scraper tool;

FIG. 2 is an elevational view taken from the blade end of the scraper tool;

FIG. 3 is a top plan view;

FIG. 4 is an elevational view of the side opposite to that shown in FIG. 1, the tool being inverted;

FIG. 5 is an elevational view taken from the handle end of the scraper tool; and

FIG. 6 is a bottom plan view of the scraper tool.

The multipurpose scraper tool, in addition to a handle and blade, has attachments including a mixing blade attached to the end of the handle, a shield attached to the handle toward the butt end thereof, and a cleaning blade attached to the handle at one side of the shield.

I claim:

The ornamental design for a multipurpose scraper tool, as shown and described.
